(57) **CLAIM**

The ornamental design for a low profile compartmentalized trading card storage box, as shown and described.

DESCRIPTION

FIG. 1 is a first perspective view of my design for a low profile compartmentalized trading card storage box having a box portion and a divider portion;

FIG. 2 is a right side view of my design for the low profile compartmentalized trading card storage box in FIG. 1;

FIG. 3 is a left side view of my design for the low profile compartmentalized trading card storage box in FIG. 1;

FIG. 4 is a front view of my design for the low profile compartmentalized trading card storage box in FIG. 1;

FIG. 5 is a back view of my design for the low profile compartmentalized trading card storage box in FIG. 1;

FIG. 6 is a top view of my design for the low profile compartmentalized trading card storage box in FIG. 1;

FIG. 7 is a bottom view of my design for the low profile compartmentalized trading card storage box in FIG. 1;

FIG. 8 is a right side cutaway view of my design for the low profile compartmentalized trading card storage box, taken along lines 8-8 in FIG. 6;

FIG. 9 is a second perspective view of the low profile compartmentalized trading card storage box in FIG. 1, shown holding a plurality of trading cards and in partial exploded view with a lid;

FIG. 10 is a top view flat pattern of the box body portion of the low profile compartmentalized trading card storage box in FIG. 1; and,

FIG. 11 is a top view flat pattern of the divider portion of the low profile compartmentalized trading card storage box in FIG. 1.

The broken lines depict environmental subject matter only and form no part of the claimed design.

1 Claim, 10 Drawing Sheets
